US00D632689S

(12) **United States Design Patent**
Busri et al.

(10) **Patent No.:** **US D632,689 S**
(45) **Date of Patent:** **** Feb. 15, 2011**

(54) **APPARATUS TO ENCRYPT AND
DISTRIBUTE DATA FOR SECURITY
APPLICATIONS**

(75) Inventors: **Saharudin Busri**, Kuala Lumpur (MY);
Wong Seck Jiong, Kuala Lumpur (MY)

(73) Assignee: **Mimos Berhad**, Kuala Lumpur (MY)

(**) Term: **14 Years**

(21) Appl. No.: **29/346,848**

(22) Filed: **Nov. 6, 2009**

(51) **LOC (9) Cl.** **14-02**

(52) **U.S. Cl.** **D14/356**; D14/313

(57) **CLAIM**

The ornamental design for the apparatus to encrypt and distribute data for security applications, as shown and described.

DESCRIPTION

FIG. 1 is a perspective view, taken from the top, of an apparatus to encrypt and distribute data for security applications according to an exemplary embodiment of the present invention;

FIG. 2 is a perspective view, taken from the bottom, of the apparatus to encrypt and distribute data for security applications of the embodiment of FIG. 1;

FIG. 3 is a top plan view of the apparatus to encrypt and distribute data for security applications of the embodiment of FIG. 1;

FIG. 4 is a left-side elevational view of the apparatus to encrypt and distribute data for security applications of the embodiment of FIG. 1;

FIG. 5 is a front elevational view of the apparatus to encrypt and distribute data for security applications of the embodiment of FIG. 1;

FIG. 6 is a right-side elevational view of the apparatus to encrypt and distribute data for security applications of the embodiment of FIG. 1;

FIG. 7 is a rear elevational view of the apparatus to encrypt and distribute data for security applications of the embodiment of FIG. 1; and,

FIG. 8 is a bottom plan view of the apparatus to encrypt and distribute data for security applications of the embodiment of FIG. 1.
